UNITED STATES PATENT OFFICE.

BRYAN P. JOYCE, OF WASHINGTON, DISTRICT OF COLUMBIA.

COUNTERPOISE.

Application filed October 10, 1921. Serial No. 508,920.

(FILED UNDER THE ACT OF MARCH 3, 1883, 22 STAT. L., 625.)

To all whom it may concern:

Be it known that I, BRYAN P. JOYCE, a citizen of the United States and a resident of Washington, District of Columbia, have invented an Improvement in Counterpoise, of which the following is a specification.

The invention described herein may be used by the Government, or any of its officers or employees in prosecution of work for 10 the Government, or by any other person in the United States, without payment to me of any royalty thereon.

The subject of this invention is a counterpoise intended for use with pivotally mounted bodies but more especially for use with guns.

With the advent of aircraft in war it became necessary to so mount guns that they would be susceptible of high angles of elevation and, to accomplish this without unduly increasing the height of the mount it is essential that the trunnions or pivot point of the gun be moved from a position near the center of gravity of the gun to a point 25 well to the rear thereof or near the breech. This is necessary in order that the breech may have sufficient clearance from the ground, when the gun is in high elevation to allow for loading of the gun and permit of recoil.

With a gun so constructed, especially in long modern guns, there is an enormous weight forward of the trunnions which must be raised and lowered as the gun is elevated or depressed. In order that this weight may be moved without undue effort and with gearing of reasonable size, it becomes necessary to introduce some method of balancing the weight, and for this purpose a counterpoise is designed.

The present invention is devised to accomplish the objects set forth above by providing a simple and efficient pneumatic counterpoise so mounted as always to maintain a proper position with relation to the gun.

A further object of the invention resides in the provision of suitable packing for the counterpoise.

With these and other objects in view 50 which will appear as the description proceeds, the invention resides in the novel arrangement and combination of parts and in the details of construction hereinafter described and claimed, it being understood

that changes in the precise embodiment of 55 the invention herein disclosed may be made within the scope of what is claimed without departing from the spirit of the invention.

One practical embodiment of the invention is illustrated in the accompanying drawings, wherein:

Fig. 1 is a view in side elevation of a gun equipped with my counterpoise, the positions of the gun and counterpoise in elevation shown in dotted lines;

Fig. 2 is an enlarged view of the counterpoise, partly in longitudinal section;

Fig. 3 is a bottom plan view of the same;

Fig. 4 is a cross section taken on the line 4—4, Fig. 2;

Fig. 5 is a similar view taken on the line 5—5 of Fig. 2;

Fig. 6 is an enlarged longitudinal sectional view through a fragment of the counterpoise, showing the details of packing;

Figs. 7, 8, 9 and 10 are cross sections taken on the lines 7—7, 8—8, 9—9 and 10—10, respectively, of Fig. 6.

Referring to the drawings by numerals of reference:

In carrying out my invention I prefer to construct the counterpoise of two main members, comprising a tubular casing A, headed at one end in which is telescopically mounted a tubular plunger B, headed at its outer end. The head of the plunger B is preferably formed with a boss H which provides one supporting member of the structure, as will be hereinafter described. Conveniently secured to the head of the cylinder B is a collar B' to which is fastened, by rivets or otherwise, the rear end of the flexible casing C, herein shown as bellows like, the forward end of which is fastened to a screw cap A' threaded on the open rear end of the casing A. The purpose of the flexible casing is to protect the surface of the plunger from dust or other foreign substances.

It will be understood that spaces G with in the plunger and between the plunger walls and those of the casing is filled with fluid under pressure, conveniently air, and, in order to prevent the escape of this fluid, suitable packing must be interposed between the casing and the plunger. A preferred form of packing is shown herein and, while only one packing ring is illustrated it is evident that as many rings may be provided as

are found necessary to properly pack the members.

Referring more particularly to Fig. 6; an annular shoulder is formed on the interior of the casing A against which rests a ring D¹⁵ formed with a forwardly projecting reduced portion D¹⁷ for a purpose soon to be described. The ring is also provided with ducts or passage-ways D¹⁶ to permit the flow of lubricant therethrough. Abutting against the rear face of the ring D¹⁵ is a coiled spring D¹⁴ which is confined between said ring and an annular flange formed on the sleeve D¹³ which is interposed 15 between the spring and the plunger B to protect the polished surface of the plunger from being marred by the spring. The sleeve by preference extends between the ring D¹⁵ and the plunger as shown. The 20 annular flange of the sleeve is provided with by-passes D¹⁸ to permit the passage of lubricant to the packing ring. A formed ring D⁸ contacts the rear face of the sleeve D¹³ and with this ring are assembled metal 25 rings D¹⁰ embracing and protecting a rubber ring D¹¹ and a leather ring D¹², which latter ring rests against the outer surface of the plunger and is forced into close contact therewith by the rubber ring when the packing 30 is placed under pressure. The ring D⁸ has an annular groove in its inner face for the reception of the packing ring D⁹, preferably formed of anti-friction metal, which rests against the surface of the plunger.

Also assembled with the ring D⁸ are metal rings D⁶ which embrace and protect a rubber ring D⁷ resting against the inner surface of the casing A. In the rear of the ring D⁷ is a metal ring D⁴ which is keyed 40 to the casing as shown to prevent the same from turning as the retaining nut is screwed home and so marring or injuring the rubber ring D⁷. The retaining nut D³ is threaded into the rear end of the casing A and contacts with the ring D⁴ to hold the packing firmly in position. The ring D⁸ is counter-sunk and tapped for the reception 45 of the metal ring D¹ carrying a wiper or washer D² the purpose of which is to prevent dust which may have accumulated 50 upon the surface of the plunger from being drawn into this structure when the plunger is in its innermost position.

To properly lubricate and seal the packing, a chamber E is provided between the casing and the plunger and in this chamber is mounted, with a closing sliding fit, a metal ring F³ which is backed by a packing strip F² held in place against the rear face 60 of the ring by a metal ring F¹ which is secured to the ring F³ by rivets or otherwise. Lubricant is forced into this chamber through the valve K causing the ring F³ to move to the forward end of the chamber 65 and rest against an annular shoulder formed

in the casing. The projecting reduced portion D¹⁷ of the ring D¹⁵ prevents ring F³ from moving to the rear a sufficient distance to block or foul the valve K. Lubricant from the chamber E will be forced through the ducts D¹⁶ and by-passes D¹⁸ and will serve to properly lubricate the packing.

In the head of the casing A is mounted a valve L through which fluid under pressure is admitted to the space G.

Encircling the casing A is a band J from diametrically opposite portions of which extend the trunnions J'.

The counterpoise is preferably mounted as follows:

The gun carriage M has formed thereon a lug N provided with a hemispherical socket for the reception of the boss H. Crank arms, one of which is shown at Q, are rigidly secured to the extending end of the trunnion P of the gun S and these crank arms are apertured for the reception of the trunnions J of the counterpoise.

With the gun in horizontal position the weight forward of trunnion P is sufficient to counterbalance the expansive force of the fluid in the space G of the counterpoise and, as the gun is elevated the expansive force of the fluid is exerted through the crank arms Q and the trunnions P to partially counterbalance the weight of the forward end of the gun and so render the elevation thereof comparatively easy.

What I claim is:

1. The combination of a gun and its carriage, the carriage provided with a lug having a hemispherical socket, a tubular plunger headed at one end, a boss formed on the head of the plunger and resting in the socket, a tubular casing in which the plunger telescopes, a connection between the gun and the casing, a flexible casing inclosing the extruding end of the plunger and connected to the plunger and the tubular casing, packing between the plunger and the tubular casing, a sealing chamber adjacent the packing, an air chamber between the plunger and tubular casing, a ring movable in the sealing chamber for sealing the passage way between the air chamber and the sealing chamber, a valve for admitting lubricant to the sealing chamber, means for preventing the ring from blocking the valve and a valve for admitting fluid under pressure to the air chamber.

2. The combination with a gun and its carriage, the carriage provided with a socket, of a hollow plunger headed at one end, a boss formed on the head and resting in the socket, a hollow casing headed at one end into which the plunger telescopes, means for connecting the casing to the gun, packing between the plunger and the casing, a sealing chamber adjacent the packing, an air chamber between the plunger and the casing,

3. A ring movable in the sealing chamber for sealing the passage-way between the chambers, a valve for admitting lubricant to the sealing chamber, means for preventing the ring from blocking the valve and a valve for admitting fluid under pressure to the air chamber.
4. The combination with a pivotally mounted body and its support, said support provided with a socket, of a hollow plunger headed at one end, a boss formed on the head and resting in the socket, a hollow casing into which the plunger telescopes, a connection between the casing and the body, packing between the plunger and the casing, a sealing chamber adjacent the packing, means for admitting lubricant to the chamber, an air chamber between the plunger and casing and means for admitting fluid under pressure to the air chamber.
5. A ring movable in the sealing chamber for sealing the passage-way between the air chamber and the sealing chamber, a valve for admitting lubricant to the sealing chamber, means for preventing the ring from blocking the valve and a valve for admitting fluid under pressure to the air chamber.
6. A counterpoise, embodying a plunger, a casing into which the plunger telescopes, a packing between plunger and casing, a sealing chamber adjacent the packing, an air chamber between the plunger and casing, a ring movable in the sealing chamber for sealing the passage-way between the chambers, a valve for admitting lubricant to the sealing chamber, means for preventing the ring from blocking the valve and a valve for admitting fluid under pressure to the air chamber.
7. A counterpoise, embodying a plunger, a casing into which the plunger telescopes, a packing between the plunger and casing, a sealing chamber adjacent the packing, means for admitting lubricant to the chamber, an air chamber between plunger and casing and means for admitting fluid under pressure to the air chamber.

BRYAN P. JOYCE.
